UNITED STATES PATENT OFFICE

135,371

DESIGN FOR A JEWELRY FINDING OR SIMILAR ARTICLE

Rex Hendrix, Ruth, Nev.

Application November 17, 1942, Serial No. 108,797

Term of patent 3½ years

To all whom it may concern:

Be it known that I, Rex Hendrix, a citizen of the United States, residing at Ruth, in the county of White Pine and State of Nevada, have invented a new, original, and ornamental Design for a Jewelry Finding or Similar Article, of which the following is a specification, reference being had to the accompanying drawing, forming part thereof.

Figure 1 is a view in elevation of an ornamental design for a jewelry finding or similar article embodying my new design, and

I claim:

The ornamental design for a jewelry finding or similar article, as shown.

REX HENDRIX.
